CHARACTER TRANSMITTING SYSTEM

Helmut Pflügner and Ernst Sohn, Berlin-Mariendorf, Germany, assignors to C. Lorenz Aktiengesellschaft, Berlin-Tempelhof, Germany, a company

Application October 31, 1936, Serial No. 108,576
In Germany October 31, 1935

1 Claim. (Cl. 178—11)

It is well known to transmit characters by resolving each character into dots which are transmitted from a sending station to a receiving station with the aid of the methods used in picture telegraphy. It is also known to make up the transmitting apparatus after the manner of a typewriter and to send the component parts of the respective character with the aid of storing means in the shape of discs provided with conductive segments or conductive foils or cam discs operating contacts or the like, such discs being moved in combinations according to the character to be transmitted, as is the case with the so-called picture writers.

Further it is known to dispense with special apparatus for synchronizing. To such end each signal that is sent is at the receiving station several times written down on the recording tape. Hereby it is attained that in the case of a departure from synchronism at least one of the character lines recorded at the receiving station shall be complete, i. e. readable. This method however has the disadvantage that the record lines are more or less oblique on the paper tape, in accordance with the degree of the departure from synchronism. This method is nevertheless sufficient in many cases, and it is so especially if the transmitted telegrams are only intended for a small circle of persons who have daily or frequently to do with these telegrams. If however the telegrams are intended for the general public then a recording of this nature is frequently annoying, as it requires a certain skill in order to read them quickly.

The invention therefore has for its object to record the characters only once and to employ a synchronizing method which shall be as simple as possible and by which on the one hand the time required for transmission will not or will only slightly be increased, while on the other hand the expenditure in apparatus on the receiving side shall be as small as possible. For this purpose the synchronizing impulses are given in the pauses between the picture lines which serve to compose the characters, and they are also caused to clutch the writing device to the continuously running motor, the writing device remaining in this condition during one revolution.

The invention is described hereafter by way of example, reference being had to the accompanying drawing in which

Fig. 1 is a diagram illustrating the method employed in connection with the novel arrangement. Fig. 2 is a partially diagrammatic per-

spective view showing one embodiment of this arrangement. Fig. 3 is an elevation showing a modification of the arrangement represented in Fig. 2. Fig. 4 is an end view to Fig. 3.

In Fig. 1 a receiving tape 1 and some characters A, B, C, D thereon are represented. On tape 1, for each picture line 2 extending transversely of the tape, a short synchronizing impulse 3, given at the commencement of the picture line, is marked as a dot. In the case represented by 10 way of example, the characters are reproduced with the aid of seven picture lines each. In the pauses between the characters no synchronization is effected because it is not necessary to synchronize here.

For the sake of simplicity, only those parts of the picture writer are represented in Figs. 2, 3, 4 which are concerned with the invention, other parts not being shown as they are not necessary for a complete understanding of the invention.

The writing device represented in Figs. 2, 3, 4 has a so-called Meyer edge C and a counter edge S adapted to cooperate therewith in order to record the impulses in a well known manner.

On a cylinder or barrel B the edge C is arranged as a helical crest. Barrel B is mounted loosely on the shaft A of the motor M. Coiled around shaft A is a helical spring F one end of which is fixed to barrel B in the manner, for instance, appearing from Figs. 3 and 4. This spring tends to contract in order to come in frictional contact with shaft A and has a free end adapted to be engaged by a tooth or stop n. If so engaged, spring F is out of frictional contact with shaft A. This state of things is represented 35 in all the three Figs. 2, 3, 4.

Edge S is jointedly connected with a lever K fulcrumed at e. Lever K is the armature of an electromagnet Q and is under the action of a retractile spring E.

The constructional features as thus far described are peculiar to both the arrangement shown in Fig. 2 and that shown in Figs. 3 and 4. The differences between the two are as follows:

In the arrangement according to Fig. 2, stop n forms part of a lever H fulcrumed at d. This lever is the armature of an electromagnet R and is attached to a retractile spring D.

In the arrangement illustrated in Figs. 3 and 4, stop n forms part of a leaf spring f mounted at 50 g. Spring f carries a tappet a that projects into the path of the edge S but does not extend beyond edge C, being spaced at about 0.1 millimetre, or nearly so, from the circumference thereof. Edge C has a recess b.

The mode of action is as follows:

In the arrangement shown in Fig. 2, each synchronizing impulse, given at the commencement of a picture line, energizes magnet R which then 5 attracts lever H. Hereby the free end of the spring F is released. This spring in its effort to contract comes in frictional contact with the rotating shaft A and thus acts to clutch the barrel B to this shaft. The device B, C is hence caused 10 to share in the rotation of shaft A until the free end of the spring F comes against tooth n, lever H having been restored to normal by spring D after the cessation of the synchronizing impulse. By the free end of spring F striking the 15 tooth n, this spring is expanded so as to release shaft A. The device B, C therefore ceases to rotate, having performed one revolution in this way.

Magnet Q, Fig. 2, is energized by the picture 20 impulses, and by means of lever K and spring E causes the edge S to be pressed against edge C in the rhythm of these impulses.

As the arrangement shown in Fig. 2 has two 25 magnets, namely, magnet R for the synchronizing impulses and magnet Q for the picture impulses, there must be a switching device for changing from one magnet to the other. An arrangement of cam discs or any other suitable 30 device may serve this purpose.

Such additional control means is superseded in 35 the arrangement shown in Figs. 3 and 4, magnet Q here being arranged to receive both synchronizing and picture impulses.

Each impulse acting on magnet Q, Fig. 4, will 40 be means of lever H and spring D actuate the edge S in the manner described with reference to Fig. 2. When a synchronizing impulse arrives the position of the barrel B and edge C is that represented in Figs. 3 and 4. As a result 45 edge S is allowed by recess b to strike the tape a so as to depress the spring f momentarily. Tooth n therefore releases the free end of the spring F which then acts to clutch the device B, C to the rotating shaft A, as described with 50 reference to Fig. 2. Since owing to recess b edge S does not yet come against edge C, the synchronizing impulse is not recorded on the paper tape P which for the sake of simplicity is shown in Fig. 3 only. The picture impulses however now arriving cause the edge S to be pressed against the

rotating edge C, as described. After one revolution made by device B, C the spring F is again caught by tooth n and the rotation of B, C thus stopped. It is necessary to such end that after this revolution the spring f does not vibrate any longer, because otherwise the free end of the spring F may happen not to be arrested by tooth n and thus cause a picture line to be out of phase. 5

In the arrangement according to Figs. 3 and 4 the synchronizing impulse, given at the beginning 10 of each picture line, is not delivered separately from the picture impulse but is given in conjunction therewith, without however being recorded. The fact that the synchronizing impulse is not recorded is due to recess b, as described before. 15 Paper tape P is during the recording moved continuously, this being contrary to the start stop writers. The advantage of the novel arrangement resides in the fact that the device can be made to occupy a comparatively small space 20 while being simple in mechanical and electrical relation. If the synchronizing impulse happens to be indistinct or even suppressed, then only a phase displacement of a picture line will occur without the entire picture being less easy to read, 25 because whenever a synchronizing impulse is missing, the first picture sign will instead actuate the described clutch or a clutch of a suitable other construction.

What is claimed is:

A recording for recording characters composed 30 of a plurality of electric impulses which when recorded form the separate characters, comprising a transcribing means including a shaft, a cylinder provided with a helical edge rotatably mounted on said shaft, a motor for continuously rotating said shaft, a spring clutch including a helical spring wound around said shaft and having a free projecting end for coupling said cylinder to said shaft, means including a detent engaging 40 the free end of said spring and tending to force it in a direction opposite to the winding of the spring for holding said clutch out of engagement with said shaft in the absence of signals, and means responsive to receipt of a synchronizing 45 impulse to effect engagement of said clutch with said shaft.
